UNITED STATES PATENT OFFICE.

NATHAN P. LEVIN, OF DETROIT, MICHIGAN.

ENGINE CONSTRUCTION.

1,405,235.

Specification of Letters Patent. Patented Jan. 31, 1922.

Application filed June 3, 1918. Serial No. 237,885.

To all whom it may concern:

Be it known that I, NATHAN P. LEVIN, a citizen of the United States of America, residing at Detroit, in the county of Wayne and State of Michigan, have invented certain new and useful Improvements in Engine Constructions, of which the following is a specification, reference being had therein to the accompanying drawings.

10 This invention relates to engines and refers more particularly to engines of the internal combustion type.

Among the objects of the invention is to increase the horsepower output through increasing the volumetric efficiency of the engine. The invention also resides in the novel arrangement for securing this result by increasing the valve capacity and also in arranging the parts so that each valve per-

20 forms a double function.

Among other features of the invention is the arrangement whereby the valve operating cam can be shaped to hold the valve open during double or more than double the time that the valves are normally held open in a four cycle engine; that is, in the present construction the valve is held open during the whole of the intake and exhaust portion of the cycle, thus permitting the maximum lift at the point where the valve starts to function as an intake valve; to provide a construction which can be applied to ordinary gas engines of standard construction without material change; and in general to 30 provide an improved and simplified construction of the character above referred to.

In the drawings:

Figure 1 is a diagrammatic sectional view of an engine cylinder embodying my invention;

40 Figure 2 is a cross-section on line 2—2 of Figure 1;

Figure 3 is a view showing a slightly modified construction;

45 Figure 4 is a cross-section on line 4—4 of Figure 1.

Describing in detail the particular embodiment of my invention shown in the drawings, A designates a cylinder of an internal combustion engine and B the cylinder head having in the top a valve seat C which is in open communication with a passage D. At its outer end this passage opens at E into the atmosphere, the opening being controlled 50 by the usual butterfly valve F. An additional throttle valve G is preferably em-

ployed just above the valve seat and there may also be employed the usual auxiliary air port G' opening into the passageway D.

Communication between the passageway 60 D and the interior of the cylinder is controlled by a poppet valve H which is normally held to its seat C by a spring H' sleeved upon the stem H². It will be noted that there is but a single passageway leading 65 to the interior of the cylinder and that this passageway is controlled by a single valve H, although it will, of course, be understood that one or more valves, all operating in the same manner, can be employed.

70 The discharge end I of the carbureter J is positioned in the passageway D so as to be subjected to the suction of the incoming air and this discharge end or nozzle I of the carbureter is controlled by a valve J' operated by a rock-arm K and rod K' from the cam K² on the cam-shaft L. This shaft also has a cam L' which is connected by a rod L² to the rock-arm L³, the end of which extends over the top of the stem H² of the valve H. 80 These cams are so arranged that the cam L' will hold the rod L² in lifted position in excess of 180° of movement of the cam-shaft L, while the cam K² holds the rod K' in lifted position throughout 270° of movement of 85 the cam-shaft L, thus allowing nozzle I to be open only during the suction stroke.

While in certain of its aspects the invention is not limited to the particular type of engine mentioned, it is shown and described 90 in connection with the ordinary four cycle engine having the ordinary type of carbureter and the usual explosion, compression and exhaust strokes. Moreover, this construction does not compel the least variation 95 from standard four cycle practice. Thus for example the carburation, the duration of each cycle, the timing of the valves and ignition, the manner of priming the engine, the throttle control and other parts can be the 100 same as in the standard automobile or aeroplane engine, and my invention can be applied to ordinary four cycle engines by simply substituting a different cylinder head.

In the present novel arrangement of parts 105 the valve H is held open during both the exhaust and the suction strokes. By this arrangement the cam L' can be shaped to cause a relatively wide opening of the valve H and at the time of completion of the 110 exhaust stroke this valve will have reached its greatest degree of opening and stand in

this position at the start of the suction stroke. When the piston B' starts downward on its suction stroke the cam K² will have permitted the opening of the fuel valve 5 J' by the spring J² so that the inrushing air will carry with it a proportionate amount of fuel and vaporize it as it passes into the cylinder.

From the above description it will be obvious that a great increase in the horsepower output, due to the increase in the volumetric efficiency of the engine, will be produced, owing to the fact that a larger number of valves can be employed for a given size of cylinder. Thus if the cylinder head was arranged to accommodate four valves in the ordinary engine, two of these would be used for exhaust and two for intake, whereas in my construction the entire four valves would be used both for exhaust and for intake, thus doubling the opening through which fuel can be taken into the cylinder. Also since the valve is held open in excess of 180° of movement of the cam-shaft and is at its widest open position at the start of the suction stroke, each valve will afford more than twice the amount of opening that it would under the old practice in four cycle engines. Combining these two features it will be understood that at least four times the valve opening is provided for the same size of valve.

This type of engine is peculiarly adapted for aeroplane work as it gives a wide open exhaust and is capable of operating efficiently at very high speeds. By using a single control valve for the inlet and exhaust, the incoming air will tend to extract heat from the valve, thus keeping the latter cool to a proper temperature. Also the rapid motion of the aeroplane relative to the air will tend to dissipate the exhaust gases from around the valve.

Not only is the engine one of great efficiency, but owing to the minimum number of working parts and the simplicity of con-

struction it can be very economically constructed. Various changes, however, in the number of valves and in the arrangements and combinations of the passageways can be made. One such modification is shown in Figure 3 in which the passageway D of Figure 1 is omitted and the air and fuel are admitted into the spider construction M just above the valve seat C.

What I claim as my invention is:—

1. In an internal combustion engine, the combination with a cylinder, a passage-way leading therefrom forming both an inlet and an exhaust opening and having a venturi portion, a valve controlling said passage-way for both inlet and exhaust purposes, a liquid fuel discharge nozzle extending into and opening within said venturi portion, a second valve controlling said discharge nozzle, and means for actuating said valves in proper timed relation.

2. In an internal combustion engine of the four cycle type, the combination with the cylinder thereof, of a passage-way leading therefrom forming the inlet and exhaust opening, and having a venturi portion and a single external orifice, a single valve controlling said passage-way for both inlet and exhaust purposes, a liquid fuel discharge nozzle opening into said venturi portion, a second valve controlling said discharge nozzle, and means for actuating said valves in proper timed relation.

3. In an internal combustion engine the combination with a cylinder, of a passage-way leading therefrom forming both an inlet and exhaust conduit, a valve controlling said passageway for both inlet and exhaust purposes, cam control means for said valve, means for delivering fluid fuel to said passageway, and a mixture control valve intermediate the first mentioned valve and said fuel supply means.

In testimony whereof I affix my signature.

NATHAN P. LEVIN.
